Primary Examiner — Rashida Johnson(74) *Attorney, Agent, or Firm* — Womble Carlyle Sandridge & Rice LLP**CLAIM**

The ornamental design for a ski jacket, as shown and described.

DESCRIPTION

FIG. 1 is a front perspective view of a ski jacket showing our new design;

FIG. 2 is a front elevational view the ski jacket from FIG. 1; FIG. 3 is a rear elevational view of the ski jacket from FIGS. 1-2;

FIG. 4 is a left side elevational view of the ski jacket from FIGS. 1-3;

FIG. 5 is a right side elevational view of the ski jacket from FIGS. 1-4;

FIG. 6 is a top plan view of the ski jacket from FIGS. 1-5; and, FIG. 7 is a bottom plan view of the ski jacket from FIGS. 1-6. The broken lines are for the purposes of illustrating environment only. None of the broken lines form part of the claimed design.
